UNITED STATES PATENT OFFICE.

EMORY A. BEDIENT, OF ERIE, PENNSYLVANIA, ASSIGNOR TO GLEN MANUFACTURING COMPANY, OF ELLWOOD CITY, PENNSYLVANIA.

DESIGN FOR A FABRIC FOR MATS.

40,421.

Specification for Design.

Patented Dec. 28, 1909.

Application filed October 20, 1902. Serial No. 128,084. Term of patent 14 years.

To all whom it may concern:

Be it known that I, EMORY A. BEDIENT, a citizen of the United States, residing at Erie, in the county of Erie and State of Pennsylvania, have invented a new, original, and ornamental Design for a Fabric for Mats, of which the following is a specification, reference being had to the accompanying drawings, forming a part thereof.

The figure is a plan view of a fabric showing my design.

I claim—

The ornamental design for a fabric for mats, as shown.

EMORY A. BEDIENT.
